UNITED STATES PATENT OFFICE

LOUIS L. ISSELHARDT, OF MARION, INDIANA, ASSIGNOR TO SUPERIOR PAPER PRODUCTS CO., OF MARION, INDIANA, A CORPORATION OF INDIANA

FEEDING DEVICE

Application filed April 17, 1930. Serial No. 444,943.

The invention relates generally to feeding devices and more particularly to a device for feeding blanks of paper, metal, or the like to a machine performing operations upon them.

5 The general object of the invention is to provide a novel feeding device which will insure the feeding of but one or any predetermined number of blanks at a time.

Another object is to provide such a device 10 which keeps the stock of blanks in a neat and orderly condition with the individual blanks in the stack prevented from adhering to one another.

Another object is to provide such a device 15 in which warped blanks may be handled without danger of clogging the device.

Other objects and advantages will become apparent from the following description taken in connection with the accompanying 20 drawing, in which:

Figure 1 is a view taken in a plane indicated by the line 1—1 of Fig. 2 and embodying the features of the invention.

Fig. 2 is a vertical section taken on the 25 line 2—2 of Fig. 1.

Fig. 3 is a fragmentary view taken on the line 3—3 of Fig. 2.

While the invention is susceptible of various modifications and alternative constructions, I have shown in the drawing and will herein describe in detail the preferred embodiment, but it is to be understood that I do not thereby intend to limit the invention to the specific form disclosed but intend to 30 cover all modifications and alternative constructions falling within the spirit and scope of the invention as expressed in the appended claims.

A device embodying the features of the 40 invention is adapted to feed blanks as for paper plates or the like to a machine such as a press for dishing the blank. The device comprises generally a pair of feed rolls, a rack for holding a stack of blanks, and means 45 for pushing one or any predetermined number of blanks at a time into said rolls to pass to the machine, and for keeping the blanks in the stack from sticking to each other and in an orderly condition.

50 As shown in the drawing, the present em-

bodiment of the invention comprises a pair of spaced frame members 10 and 11 lying in parallel vertical planes, each member having a flange 12 adapted to be attached to the machine (not shown) in which an operation 55 is to be performed on the blanks.

A rack, supported by the frame members 10 and 11, is provided for holding a stack of blanks A so that the plane of each blank slopes downwardly toward the machine. 60 The rack comprises a plurality of guide members 13, 14 and 15 and a relatively narrow bed 16. The guide members are arranged to extend up the sides of the stack and are made of flat strips of metal, the member 13 extending up the forward side of the stack at an angle to the vertical so that the front edge of each blank rests against it. To support the member 13, a bar 17 extends between the frame members 10 65 and 11 and is attached thereto and to the guide member 13. The bed 16 is supported by a pair of brackets 18 which are respectively attached to the frame members 10 and 11, and the guide members 14 and 15 are attached to the bed 16 and are adjustable for 70 different sizes of blanks.

To permit the removal of blanks from the rack, one or any predetermined number at a time, the bed 16 has a finger 19 at its forward end which is spaced from the lower end of the forward guide member 13 an amount sufficient to permit but one or the predetermined number of blanks to pass therebetween at a time. The finger 19 is pivoted to the bed 16 85 by means of a screw 20, and may be adjusted relative to the guide member 13 and locked in its adjusted position by a screw 21, so that blanks of different thicknesses may be accommodated.

To carry blanks from the rack into the machine, a pair of rolls 22 and 23 are mounted adjacent the opening between the finger 19 and the guide member 13. The lower roll 22 is keyed to a shaft 24 which is supported in bearings formed on the frame members 10 and 11, while the upper roll 23 is held in yielding engagement with the lower roll 22 by a shaft 25 which is supported in bearings 90 slidably mounted in the frame members 10 95 100

and 11 and pressed downwardly by springs 26. The rolls 22 and 23 are both grooved (see Fig. 3) and the ends of the finger 19 and the guide member 13 are narrowed to fit within the grooves in the respective rolls so that the opening through which blanks leave the hopper is closely adjacent to the line of contact between the two rolls.

If a warped blank gets into the rack, it is prevented from clogging the device or from being bent out of shape or torn. The bed 16 being narrow permits a blank to lie closely thereon even though it be warped. To permit such a blank to pass easily to the rolls, the upper edge of the finger 19 and the lower end of the guide member 13 are reversely curved, as is clearly shown in Fig. 3, so that the portion of the edge of the blank which lies on the bed 16 is alined with the center of the curved portions of the finger 19 and guide member 13 and will pass therebetween without catching against the member 13.

As mentioned above, the invention includes means for pushing one or any predetermined number of blanks at a time into the feed rolls and for keeping the stack in an orderly condition. In the present instance, this means comprises a pusher bar 30 which is mounted for reciprocation in a slot in the bed 16 and extends under the stack of blanks. The front end of the bar 30 is curved downwardly away from the stack as at 31 so as to slide easily under the stack, and is bifurcated to extend on both sides of the finger 19 and to be slidably supported on the screw 20 which pivotally supports the finger 19.

In the rear end of the frame member 11, a shaft 32 is rotatably journaled which carries a crank disk 33 on its end. The crank disk 33 has a crank pin 34 to which the rear end of the pusher bar 30 is rotatably attached. Thus, as the crank rotates, the rear end of the pusher bar 30 is raised during the first part of the forward movement of the bar and then is lowered, and the front end 31 of the bar slides on the screw 20.

To catch the rear edge of the bottom blank in the stack, a projecting member is provided on the upper surface of the pusher bar 30, which member, in the present instance, is a screw 35 threaded into the bar and locked in an adjusted position by a nut. For blanks of different thicknesses or for different predetermined numbers of blanks, the height at which the screw 35 projects above the surface of the bar may be adjusted so that the screw 35 will not project above said surface more than the thickness of one or any predetermined number of blanks.

To drive the device, a drive shaft 40 is journaled in the frame members 10 and 11. Outside of the frame member 10, a clutch 41 is operated by a hand lever 42 and is mounted for connecting the shaft 40 with a source of power such as a sprocket 43. On the opposite end

of the drive shaft 40 adjacent the frame member 11, a gear 44 is mounted which meshes with a gear 45 mounted on the shaft 32 to drive the crank disk 33, and with a gear 46 mounted on the shaft 24 to drive the lower feed roll 22, the upper feed roll 23 being driven by a gear mounted on the shaft 25 and meshing with the gear 46.

In operation, a stack of blanks is placed in the rack and the clutch 41 is thrown in to drive the various shafts, the crank disk 33 rotating in the direction shown by the arrow in Fig. 2. Assume that the pusher bar 30 is at the forward end of its stroke. The crank then causes the bar to be lowered and moved rearwardly. Before the bar has completed its rearward motion it starts to move up, so that by the time it starts to move forward again, it has been raised enough to bring the bar in contact with the bottom blank in the stack. During its forward motion, the screw 35 catches the rear edge of the bottom blank and pushes it forward between the finger 19 and the forward guide member 13 and into the rolls 22 and 23 by which it is fed to the machine.

During the first part of the forward motion of the bar 30, the crank continues to raise the rear end of the bar so that the stack is raised within the rack and pushed against the forward guide member 13 to keep the stack in an orderly condition. During the latter part of the forward motion, the bar is lowered so that the stack will fall back onto the bed 16. By this alternate raising and letting the stack fall, the individual blanks in the stack are jarred and loosened so that they will not adhere to each other. From the above description it is obvious that I have provided a novel feeding device which will insure the feeding of but one or any predetermined number of blanks at a time, and in which the stack of blanks is kept in a neat and orderly condition. It is also apparent that the device will handle warped blanks without danger of being clogged.

I claim as my invention:

1. A device for feeding blanks for paper plates or the like comprising, in combination, a pair of feed rolls, a rack for holding a stack of blanks and comprising a plurality of guide members and a bed sloping downwardly toward said rolls, said bed being relatively narrow to permit warped blanks to lie closely thereon, one of said guide members having its lower end adjacent said rolls, the forward end of said bed and the lower end of the guide member adjacent said rolls being reversely curved to permit a warped blank to pass easily therebetween, and a pusher bar movably mounted centrally of said bed and having a longitudinal movement in the plane of said bed to move the bottom blank or predetermined number of blanks of the stack into said rolls and an up-

ward movement to raise the blanks in the stack and move them against the guide member adjacent the rolls to keep the stack in an orderly condition.

2. A device for feeding blanks for paper plates or the like comprising, in combination, a pair of relatively narrow feed rolls having grooves in their peripheries, a rack for holding a stack of blanks and comprising a plurality of guide members and a bed which is relatively narrow to permit warped blanks to lie closely thereon and having its forward end extending into the groove in the lower roll, one of said guide members having its lower end extending into the groove in the upper roll to form an opening through which the bottom blank or predetermined number of blanks of the stack may pass to the feed rolls, the adjacent ends being adjustable relatively to each other to provide for blanks of different thicknesses and being reversely curved to permit a warped blank to pass easily therebetween, and a pusher bar movably mounted centrally of said bed and adapted to slide the bottom blank through said opening.

3. A device for feeding blanks for paper plates or the like comprising, in combination, a pair of feed rolls, a rack for holding a stack of blanks and including a bed sloping downwardly toward said rolls and having a slot therein, and means for pushing the bottom blank or predetermined number of blanks of the stack into the feed rolls, said means comprising a bar having its forward end slidably supported in said slot, and a crank attached to the rear end of said bar for moving it forwardly to push the bottom blank into the rolls and for moving it upwardly to lift the stack and loosen the blanks to prevent them from adhering to each other.

4. A device for feeding blanks for paper plates or the like comprising, in combination, a pair of feed rolls, a rack for holding a stack of blanks and including a bed sloping downwardly toward said rolls and having a slot therein, and means for pushing the bottom blank or predetermined number of blanks of the stack into said rolls, said means comprising a bar slidably supported at its forward end in said slot and having an adjustable member projecting from its upper surface to catch the rear edge of said bottom blank or blanks, said adjustable member comprising a screw threaded and locked to said bar, and a crank attached to the rear end of said bar and causing said bar to have an upward motion to lift the stack during the forward motion of said bar in pushing said bottom blank into said rolls.

5. A device for feeding blanks for paper plates or the like comprising, in combination, a pair of relatively narrow feed rolls mounted with their axes horizontal and each having a groove in its periphery, a rack for hold-

ing a stack of blanks piled one on top of the other in face to face relation, said rack comprising a relatively narrow bed extending toward said rolls with its forward end extending into the groove in the bottom roll, and a substantially vertical guide member positioned at the front of the stack with its lower end extending into the groove in the upper roll, the forward end of said bed and the lower end of said guide member being spaced apart to form an opening through which the blanks may pass one at a time, and means for sliding the bottom blank along said bed and through said opening to said rolls.

6. A device for feeding blanks for paper plates or the like comprising, in combination, a rack for holding a stack of blanks piled one on top of the other in face to face relation and comprising relatively narrow bottom and forward supports lying in a single vertical plane extending in the direction of feed of the blanks and together forming an opening through which the bottom blank may pass, a pair of relatively narrow feed rolls mounted in said plane adjacent said opening, and means for sliding the bottom blank through said opening to said rolls.

In testimony whereof, I have hereunto affixed my signature.

LOUIS L. ISSELHARDT.
